PUMPING APPARATUS

Walter H. Tinker, St. Louis, Mo., assignor to
Fairbanks, Morse & Co., Chicago, Ill., a corpora-
tion of Illinois

Application May 7, 1949, Serial No. 92,050

3 Claims. (Cl. 103—5)

1

This invention relates to fluid pumping apparatus of the pressure pump-jet character for use in deep well and shallow well applications.

The invention consists in an improved housing assembly having chambers, ports and passages arranged in a manner such that a jet pump may be internally or externally associated therewith and caused to pump fluid into a pressure pump impeller disposed in the housing at an advantageous location, the selective association of the jet pump being made possible by the use of accessory parts which are interchangeable, but easily installed in predetermined association with the housing.

The invention also consists in the details of the construction of such a housing assembly, wherein an advantageous disposition of housing chambers and external and internal ports furnishes the basis for associating the pressure pump and jet pump in a deep well and shallow well fluid pumping circuit with a minimum of confusion in the order of connecting conduits for the flow of fluid from the well and between the pumping apparatus and a tank.

A preferred embodiment of the pumping apparatus exhibiting the above stated characteristics is illustrated in the accompanying drawing, wherein:

Fig. 1 is a sectional elevational view of the improved pumping apparatus as adapted for deep well application,

Fig. 2 is a plan view, partly in section, of the deep well pump application as seen along line 2—2 in Fig. 1,

Fig. 3 is a further, enlarged sectional view, in plan, of the improved housing when conditioned for deep well application, the view being taken at line 3—3 in Fig. 1,

Fig. 4 is an elevational view of the improved housing as seen at line 4—4 in Fig. 2, and

Fig. 5 is a view similar to Fig. 3, but illustrating the modifications required to adapt the same for shallow well use, with the jet pump internally of the housing.

The present apparatus is an improvement on the pumping apparatus disclosed in a copending application of Walter H. Tinker, filed on May 7, 1949, and bearing Serial No. 92,049. This application is directed to the improvements in the housing assembly, as will now be described in detail.

Considering the views of Figs. 1 to 4, inclusive, the pumping apparatus includes a housing assembly 10 carrying an electric motor 11 for operating the impeller 12 of the pressure pump

disposed within the housing. A jet pump unit 13, in this case located in a well (not shown) is connected to the housing 10 by a pair of conduits 14 and 15, and the jet pump is provided with a fluid intake or foot valve means 16. In Fig. 2, the fluid storage tank 17 is seen to be connected with the housing by a conduit 18.

More specifically, the housing assembly 10 includes a lower or base casting member 20 having an upper wall 21 formed with an impeller bowl 22, the suction port of which is at 23. The upper wall 21 is supported by the depending skirt 24, and this skirt is characterized by a flattened wall portion 25 along one side, in which

15 are grouped ports 26, 27 and 28. These ports respectively receive, in threaded relation, the conduits 14, 15 and 18. At one end zone of the wall 25, the skirt is further formed to provide a flat wall portion 29 (Fig. 3) at right angles 20 to the wall 25. The wall 29 is recessed at 31 in the zone of a port 32 inwardly off-set from the outer face of the wall 29. Adjacent the port 32 and its recess 31, a second port or opening 33 is formed to open through the wall portion 29.

25 The internal space of the base casting 20 adjacent wall portions 25 and 29 is suitably divided into a plurality of chambers having a predetermined association with the skirt ports, above indicated. As may be seen in Fig. 3, a pair of

30 elongate walls 34 and 35 are arranged in spaced relation to define a chambered space 36 having the ports 27 and 33 located at its opposite ends. The central area of space 36 is somewhat enlarged so that it will include the impeller bowl 35 inlet port 23 in its upper surface. Thus, space 36 communicates with the bowl 22, and will assume the function of a suction chamber for the impeller 12 in the bowl 22, and the entire fluid input to the base member passes through this 40 chamber.

The outer wall 25 and inner wall 35 define a space which is divided by the transverse wall 37 into a pair of chambers 38 and 40. A common wall or floor 39 (Figs. 1 and 4) is associated 45 with each of chambers 36, 38 and 40, and the upper wall 21 completes the formation of these chambers. The chamber 38 is associated with the skirt wall port 26 and is further provided with a port 41 (Figs. 1, 2 and 4) opening upwardly through the wall 21, and an orifice or port 42 in the transverse wall 37 which opens to

50 the adjacent chamber 40. The chamber 40, in like manner, is associated with the skirt port 28, and is further located between the axially aligned 55 ports 32 and 42 respectively positioned in the

recess 31 and in the transverse wall 37. Pressure chamber 38 receives the entire flow of fluid from the impeller and acts to divide the same for flow through port 26 and toward port 42, as will appear presently.

The housing assembly 10 also includes an upper casing member 43 enclosing the upper wall 21 of the base member about its periphery, and forming a fluid discharge chamber for the impeller 12. The casing 43 also incloses a suitable diffuser ring member 44 immediately surrounding the impeller and cooperating with the bowl 22 to provide an impeller enclosure having the fluid discharge passages 45. The impeller, of generally conventional form, has its suction eye 46 in the suction port 23 and a plurality of fluid passages 47 outwardly opening to the diffuser ring 44. The fluid pumped by this impeller enters the discharge chamber 48 (Fig. 1) in the casing member 43 and is constrained to flow through the port 41 in wall 21 to the lower chamber 38. Chamber 38 thus becomes a pressure chamber and acts to direct the fluid toward ports 26 and 42, depending upon the pumping circuit chosen.

In a deep well installation, where the jet pump 13 is located in the well or other source of fluid supply, the pumping circuit chosen will conform to that shown in Figs. 1, 2 and 3. Thus, the jet pump 13, through its suction chamber 50 between the nozzle 51 and Venturi tube 52 lifts fluid from the source for flow through conduit 15 to the suction chamber 36 at port 27. The impeller entrains the fluid from chamber 36 and forces it into chamber 48 where it passes downwardly through port 41 to the pressure chamber 38. A part of the fluid in chamber 38 returns to the jet pump 13 by way of port 28, conduit 14 and the elbow passage 53 in the jet pump fitting 54.

The effective fluid delivery from the pump housing 10 to tank 11 through conduit 18 is from the chamber 40 by way of the port 42 in transverse wall 37. Since the jet pump 13 requires a certain minimum supply of fluid under pressure to energize the same, the fluid reaching chamber 38 under pressure is divided in such a way that an adequate supply continuously flows to conduit 14 and the excess fluid is permitted to pass to the chamber 40 for supply to tank 11. The division of fluid is automatically regulated by a valve assembly 56 (Fig. 3) which is responsive to the pressure developed in chamber 38.

The control valve assembly 56 is mounted on a suitable plate 57 which fully covers the housing ports 32 and 33, but allows for the inward projection of a guide sleeve 58 at port 32, the sleeve being threadedly mounted in a collar 59 carried in the plate 57. A valve element 60 has its stem 61 slidably disposed in the axial bore in sleeve 58, and the valve is urged by spring 62 to close port 42 by the valve face 63. Fluid leakage externally of the housing past the valve is prevented by a bellows member 64. The valve spring 62 is adjusted by axial positioning of the sleeve 58 so that the port 42 will be opened by valve movement at a predetermined pressure in chamber 38. It is, however, desirable to maintain a spring force on the valve to prevent collapse of the bellows under back pressure effects in conduit 18 to open the port 42.

In conjunction with the regulating valve 56, the motor 11 driving impeller 12 by its shaft 66, as shown, is supplied with a pressure responsive switch 67 in the current supply circuit represented by the cord 68. This switch has its pressure

responsive mechanism (not shown) connected through the small conduit 69 with a port 70 in wall 25 (Figs. 2, 3 and 4) and opening to the chamber 40. The end of conduit 69 shown in Fig. 1 is assumed to be a part of the other end shown in Figs. 2 and 3. Connected in this zone of the pumping circuit, the switch 67 is responsive to pressure in the tank side of the apparatus, and is set to start the motor 11 at a predetermined low tank pressure and to stop the motor when the pressure reaches a desired high value.

When converting the apparatus for use with a shallow well, the assembly is simply and quickly modified by removing the regulating valve 56 and its mounting plate 57, and substituting the jet pump nozzle 71 and Venturi tube 72, as shown in Fig. 5. The nozzle 71 is threaded into port 42 and the tube 72 is threaded into port 32 so that the jet pump suction is in chamber 40. Chamber 38 now supplies energy fluid directly to the nozzle 71. In place of the former plate 57 at wall 29, there is now used a chambered closure member 73 which receives the jet pump fluid discharge and directs such fluid to the port 33 of suction chamber 36. Since port 33 is now in use, the former fluid input conduit 15 (Fig. 3) is removed entirely and a suitable closure plug 14 is threaded into the port 27 (Fig. 5). Conduit 14 is also removed with conduit 15, and a conduit fitting 75 is mounted at port 26 for connection with a suitable part of the conduit 18 leading to the tank 11. The fluid suction conduit 76 leading from the source of fluid supply, as a shallow well, is now substituted at port 28 for that portion of conduit 18 which is necessarily removed when re-establishing the tank connection at fitting 75. The shallow well pumping circuit is now complete, and it will be observed that only two external conduits 75 and 76 are needed, both being located in the wall 25 of the base member 20.

When converting to shallow well application, or in initial installation, the motor control switch 67 has its pressure conduit 69 connected into chamber 38 at the port 77 so as to respond to tank pressure conditions for starting and stopping the motor. Thus, the switch end of conduit 69 remains as shown in Fig. 1, but its opposite end is now shown at 69' (Fig. 5). At the time conduit end 69' is connected into port 77, the plug element 78 (Fig. 3) is removed and placed in port 70 at chamber 40 (Fig. 5). The pumping apparatus is now fully converted to shallow well use, with the jet pump mounted internally of the base member 20.

The foregoing description of the improved pumping apparatus sets forth the important characteristics of structure which enables its use either for deep well or shallow well operation, and it is believed that the respective fluid pumping circuits have been sufficiently detailed to give a ready knowledge thereof without further discussion.

It is apparent that the present apparatus provides a relatively simple pump housing structure, having a novel and improved arrangement of chambers and ports for selective shallow well and deep well application. While the present embodiment is disclosed as a preference, it should be clear that certain modifications may be made herein, without departing from the intended scope of the appended claims.

I claim:

1. A pump housing assembly for pumping apparatus of the character described, comprising a unitary base member providing a top wall hav-

ing an impeller bowl and a suction port centrally in the bowl, an upper casing member seated on said base member and forming with said top wall a pump discharge chamber, said base member further providing an outer side wall having a flattened wall portion at one side of the member and a planar wall portion extending substantially normal to and adjoining one end of said flattened wall portion, a bottom wall, and wall means internally of the base member forming with said top, bottom and side walls, a plurality of chambers, one of said chambers constituting a pump suction chamber communicating with said impeller bowl through said suction port, another of said chambers constituting a pressure chamber, 15 said top wall having a port therein communicating said pressure chamber with said pump discharge chamber, said flattened wall portion being provided with a plurality of ports one associated with said suction chamber, another associated with said pressure chamber and a third port associated with a third chamber of said plurality of chambers, said planar wall portion having a port associated with said suction chamber and an opening associated with said third chamber, and said wall means internally of the base member including a wall element between said pressure and third chambers provided with an opening therein arranged in axial alignment with said opening in the planar wall portion.

2. In well pumping apparatus including a jet pump unit located in the well and having fluid pressure delivery and return conduits connected therewith, the combination of a unitary chambered member providing top, bottom, side and interior walls, forming in the member a suction chamber, a pressure chamber and a third chamber, the member further providing in said top wall an impeller bowl having a suction opening communicating with said suction chamber, an impeller operable in said bowl, casing means over said top wall and enclosing the impeller and bowl and forming an impeller discharge chamber, the member having an opening in said top wall communicating said discharge chamber with said pressure chamber, said side wall of the member including a flattened portion common to said suction, pressure and third chambers and having a plurality of ports therein, one associated with each of said suction, pressure and third chambers, the pressure delivery conduit of the jet pump unit being connected to the port associated with said pressure chamber and the return conduit of the jet pump unit being connected with the port associated with said suction chamber, said third chamber having a first aperture in an interior wall portion thereof opening to said pressure chamber and a second aperture opening through the side wall of the member, said suction chamber having a port opening through the side wall of the member in a zone thereof adjacent said second aperture of the third chamber.

a fluid storage tank having a feed conduit connected to the port associated with said third chamber, a closure element removably attached to the side wall of said chambered member in a position to close the last said port of the suction chamber and to overlie said second aperture of the third chamber, and control valve means carried by said closure element and projecting through said second aperture, providing a valve element in operative association with said first aperture, said valve means being effective for opening and closing said first aperture in response to fluid pressure variations in said pressure chamber.

5 3. A pump housing assembly for pumping apparatus of the character described, comprising a unitary base member providing a top wall having an impeller bowl and a suction port centrally in the bowl, an upper casing member seated on 10 said base member and forming with said top wall a pump discharge chamber, said base member further providing an outer side wall having a flattened wall portion at one side of the member and a planar wall portion extending substantially normal to and adjoining one end of said flattened wall portion, a bottom wall, and wall means internally of the base member forming with said top, bottom and side walls, a plurality of chambers, one of said chambers constituting a pump suction 15 chamber communicating with said impeller bowl through said suction port, another of said chambers constituting a pressure chamber, said top wall having a port therein communicating said pressure chamber with said pump discharge chamber, said flattened wall portion being provided with a plurality of ports one associated with said suction chamber, another associated with said pressure chamber and a third port associated with a third chamber of said plurality of chambers, said planar wall portion having an opening associated with said third chamber, and said wall means internally of the base member including a wall element between said pressure and third chambers provided with an opening therein arranged in axial alignment with said opening in the planar wall portion.
